UNITED STATES PATENT OFFICE

ASHLEY C. BENNETT, OF MINNEAPOLIS, MINNESOTA

AIR CLEANER

Application filed November 6, 1926. Serial No. 146,736.

This invention relates to air cleaners such as are especially adapted for use in connection with the carburetors of internal combustion engines and, generally stated, it consists of the novel devices, combinations of devices and arrangement of parts hereinafter described and defined in the claims.

The present invention belongs to a type of air cleaner disclosed and broadly claimed in my prior Patent No. 1,223,662, of date April 24, 1917, but it involves highly important novel features. The novelty of the present case is chiefly in the improvement of primary and secondary devices for producing a whirling motion of the air drawn into the cleaner, and in the cooperative arrangement of the clean air outlet means and the dust-receiving means. The cleaner is adapted to be operated in various different positions, to wit: in horizontal, vertical or oblique positions, but in the drawings I have shown the same turned with its axis horizontal and directly connected to the air intake of a carburetor, such as used in connection with internal combustion engines.

In the drawings, which illustrate said invention applied as indicated, like characters indicate like parts throughout the several views.

Referring to the drawings:

Fig. 1 is a side elevation showing the air cleaner attached to a carburetor as indicated;

Fig. 2 is an axial section taken through the air cleaner on the line 2—2 of Fig. 1; and

Fig. 3 is an end elevation looking from the left toward the right in respect to Fig. 2 and showing the casing with the dust cap removed therefrom.

The carburetor, which is indicated as an entirety by the numeral 4, is provided with the customary air intake tube 5, which, in the arrangement shown, is horizontally disposed.

The air cleaner comprises a tubular casing 6, preferably cylindrical and of sheet metal, provided at one end with a fixed head 7, which, as shown, is axially bulged at 7^a. As shown, the head 7 is secured to the adjacent end of the casing 6 by a rolled bead 8 that affords a seat for a gasket 9. The numeral 10 indicates a dust cap that is detachably

telescoped onto the end of the casing 6 and is clamped against the gasket 9 by a suitable clamping means shown as afforded by a threaded rod 11 anchored to the head 7, passed through an axial perforation in the cap 10 and provided at its outer end with a thumb nut 12. The head 7 and dust cap 10 form a dust-collecting chamber 13. The head 7 is provided adjacent to the shell 6 with a dust port 14 through which, as will herein-after appear, the dust will be thrown under the action of centrifugal force and caused to enter the dust chamber 13. At its other end, the casing 6 is provided with an axially extended clean air outlet tube 15 preferably made of such size that its projecting end can be telescoped onto the air intake tube 5 of the carburetor. An annular air intake passage 16 is formed between the tube 15 and casing 6, and in this air intake passage is an annular series of oblique circumferentially spaced primary air deflecting blades or vanes 17, which, as shown, are formed as a part of an annular sheet metal spacing ring 18 that is rigidly secured to said tube and to the casing 6, the latter connection being formed by a rolled bead 19. Spaced inward from the primary deflecting blades 17 is a series of oblique circumferentially spaced secondary deflecting blades or vanes 20, which, as shown, are formed by the expanded inner extremity of the air tube 15, the outer portions of said blades 20 being preferably slightly spaced from the interior of the casing 6. Between the primary and secondary blades, the air tube 15 has auxiliary air ports 21 that open into said tube from the annular air chamber 16.

Operation

When the air cleaner is connected to the carburetor and the engine is in operation, the suction produced in the air intake of the carburetor will, of course, produce a partial vacuum in the air tube 15 and within the casing 6 and this, as is obvious, will cause the air laden with more or less dust to be drawn into the casing. The incoming air will strike the primary deflecting blades 17 and will be caused to take up a whirling motion around 100

the air tube 15 and within the casing 6. Centrifugal force will, of course, cause the dust particles to be thrown outward and take up a whirling motion against the interior of the casing. A relatively small part of the clean air will be drawn through the auxiliary ports 21 and will take a short cut out through the clean air tube 15, but the main body of the air will continue its spiral motion and will 5 strike the secondary deflecting blades 20 and, by the latter, its whirling motion will be not only continued but accelerated or reestablished so that the main body of air, upon entering the main chamber of the casing 6, will be caused to continue its whirling motion and 10 will cause the dust, while hugging the interior of the casing, to advance spirally against the head 7 and to pass through the port 14 and into the dust chamber 13. The 15 fulged portion 7^a of the head 7 assists in deflecting the dust and affords a sort of annular track on the head 7 adjacent to the shell 6 that serves to direct the dust to the port 14. The air, freed from dust, will reverse its 20 direction of travel within the casing and will pass axially outward through the clean air tube 15 and to the carburetor. Experiments have shown that the efficiency of the air cleaner is materially increased by the use of 25 the primary and secondary air-deflecting devices for setting up the whirling motion of the air and is still further improved by the auxiliary air ports 21, which permit a considerable portion of the clean air to immediately 30 pass into the air tube 15. I have also found that the cleaning action is further improved by giving the blades 20 greater inclination than is given to the primary blades 17. The reason for this seems to be that all 35 of the air passing to the cleaner will strike the blades 17 under relatively high velocity and that a considerably reduced volume will strike the blades 20, due to the fact that some of the air is short-circuited through the ports 40 21 and it seems that the slower traveling air, striking the blades 20 in order to keep up the peripheral velocity or centrifugal action, requires a greater bevel in the blades 20. It is also important that the secondary blades 20 45 do not have contact with the shell 6, but are spaced therefrom slightly so as to permit the thin film of spirally moving dust to pass freely to the interior or main chamber of the casing.

50 It is also preferred that the secondary blades 20 be smaller than the primary blades 17, in proportion to the reduction in volume of air, which passes through said secondary blades 20, due to the ports 21 located intermediate 55 between said primary and secondary blades.

What I claim is:

1. An air cleaner comprising a tubular casing provided with an air outlet tube and 60 an air inlet passage, said air inlet passage

having spaced primary and secondary deflecting blades causing the incoming air to take up a whirling motion, said air inlet having unobstructed auxiliary ports leading therefrom from points between said primary and secondary deflecting blades and leading directly into said air outlet tube, and said casing having a dust chamber for the dust separated from the clean air. 70

2. An air cleaner comprising a tubular casing provided at one end with an axial clean air outlet tube, primary and secondary deflecting blades surrounding said tube for causing the incoming air to take up a whirling motion, and said air tube between said primary and secondary blades having unobstructed auxiliary air ports, leading directly therefrom into the clean air outlet tube to allow some of the incoming air to short-circuit therethrough to the outlet without 80 passing said secondary deflecting blades. 85

3. An air cleaner comprising a tubular casing provided at one end with an axial clean air outlet tube, primary and secondary deflecting blades surrounding said tube for causing the incoming air to take up a whirling motion, and said air outlet tube between said primary and secondary blades having unobstructed auxiliary air ports leading directly therefrom into said clean air outlet 90 tube, and said casing at its opposite end having a dust-collecting chamber into which the dust is adapted to be thrown under the action of centrifugal force. 95

4. An air cleaner comprising a tubular casing provided at one end with an axial air outlet tube and a dust-collecting chamber at its opposite end, said casing surrounding said air outlet tube having an annular air inlet and in said air inlet axially spaced series of 100 circumferentially spaced deflecting blades, the innermost of said series of circumferentially spaced blades being spaced from the inner wall of said casing to permit the thin film of spirally moving dust to pass freely 105 to the interior of the main chamber of the casing. 110

5. An air cleaner comprising a tubular casing provided at one end with an axial air outlet tube and a dust-collecting chamber at 115 its opposite end, said casing surrounding said air outlet tube and forming an annular air inlet therebetween and said tube and in said air inlet an axially spaced series of circumferentially spaced deflecting blades, the said 120 air outlet tube between said axially spaced series of deflecting blades having auxiliary air ports.

6. An air cleaner comprising a tubular casing provided at one end with an axial 125 clean air outlet tube, primary and secondary deflecting blades surrounding said tube for causing the incoming air to take up a whirling motion, and said air outlet tube between said primary and secondary blades having 130

unobstructed auxiliary air ports leading directly therefrom to said clean air outlet tube, said casing at its opposite end having a dust-collecting chamber into which the dust is adapted to be thrown under the action of centrifugal force, and said dust chamber having a dust-receiving port located adjacent to said casing.

7. An air cleaner comprising a tubular casing provided at one end with an axial clean air outlet tube, primary and secondary deflecting blades surrounding said tube for causing the incoming air to take up a whirling motion, and said air outlet tube between said primary and secondary blades having unobstructed auxiliary air ports leading directly therefrom to said clean air outlet tube, said casing at its opposite end having a dust-collecting chamber into which the dust is adapted to be thrown under the action of centrifugal force, said dust chamber having a central portion bulged axially towards said clean air outlet tube.

8. An air cleaner comprising a tubular casing provided with an air outlet tube and an air inlet passage, said air inlet passage having spaced primary and secondary deflecting blades causing the incoming air to take up a whirling motion, said air inlet having unobstructed auxiliary ports leading therefrom from points between said primary and secondary deflecting blades and leading directly into said air outlet tube, and said casing having a dust chamber for the dust separated from the clean air, in which the inner deflecting blades have greater bevel than the outer deflecting blades.

9. An air cleaner comprising a tubular casing provided at one end with an axial clean air outlet tube, primary and secondary deflecting blades surrounding said tube for causing the incoming air to take up a whirling motion, and said air tube between said primary and secondary blades having unobstructed auxiliary air ports leading directly therefrom into the clean air outlet tube to allow some of the incoming air to short circuit therethrough to the outlet tube without passing said secondary deflecting blades, in which the secondary deflecting blades have greater bevel than the primary deflecting blades.

In testimony whereof I affix my signature.
ASHLEY C. BENNETT.
